UNITED STATES PATENT OFFICE.

WILLIAM C. McWHIRTER, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

MACHINE FOR CONTROLLING RAILWAY-TRAFFIC-GOVERNING APPARATUS.

Application filed July 7, 1923. Serial No. 650,032.

To all whom it may concern:

Be it known that I, WILLIAM C. McWHIRTER, a citizen of the United States, residing at Wilkinsburg, in the county of Allegheny and State of Pennsylvania, have invented certain new and useful Improvements in Machines for Controlling Railway-Traffic-Governing Apparatus, of which the following is a specification.

10 My invention relates to machines for controlling railway traffic governing apparatus, and particularly to machines of the type comprising levers for the mechanical operation of traffic governing devices and other 15 levers for the electrical control of traffic governing devices.

I will describe one form of machine embodying my invention, and will then point out the novel features thereof in claims.

20 In the accompanying drawings, Fig. 1 is a view showing in front elevation one form of machine embodying my invention. Fig. 2 is an end view, partly sectioned, showing the machine illustrated in Fig. 1. Fig. 3 is a detail view showing, on an increased scale, the frame section G and associated parts of the machine shown in Figs. 1 and 2.

Similar reference characters refer to similar parts in each of the views.

30 Referring to the drawings, the reference character C designates a suitable framework in which are supported a plurality of mechanical levers A. Each of these levers is pivoted near its lower end at a and is adapted for the mechanical operation of a railway traffic governing device such as a railway switch. An interlocking bed B is also supported by the framework C and comprises a plurality of locking bars 1. 35 Each lever is provided with a latch 2 for cooperating with a latch plate 3 to retain the lever A in the extreme positions of its stroke, and this latch operates a rocking link 4 one end of which is connected with a crank 5. This crank is rigidly fastened to a rotatable shaft 6 which is arranged to operate one or more of the locking bars 1 by suitable means such as a segment gear 7 fixed to shaft 6 and meshing with a rack on the locking bar. The movements of each latch 2 are thus utilized to impart longitudinal motion to one of the locking bars.

Supported on framework C are a plurality of equally spaced upstanding legs D.

Extending between each two adjacent legs D 55 and supported thereby is a front frame section G of cast iron or other suitable material. The cross section of this frame section is roughly channel-shaped with the web portions extending toward the front of the machine. Each such frame section G is provided with a longitudinal, forwardly extending rib G' which divides the frame section into two longitudinal compartments which are used to contain certain apparatus 60 which I will describe more in detail herein-after.

In the left-hand portion of Fig. 1 this apparatus is omitted from the drawing to show more clearly the configuration of frame section G. A plate E of the same height and length as frame section G extends across the back of the machine between each two legs D. Each frame section G and plate E is then seen to extend from the middle of one leg D to the middle of the adjacent leg D. Each frame section G is fastened to the associated legs D by means of bolts 27 and each plate E is similarly fastened to the associated leg D by means of bolts 28. 80

Mounted on the frame section G and plate E are a plurality of electric controlling mechanisms, which I will term electric levers F. Since each lever F is separate and complete in and of itself it follows that only 85 as many of these levers as are required for controlling the equipment need be mounted on the machine. This number may or may not be equal to the number of mechanical levers required. Each electric lever comprises a suitable casing containing a rotatable spindle J operated through two bevel gears 8 and 9 by a handle H. The lever F may be used to control any desired electrical traffic controlling device such for example 90 as a railway signal. 95

The spindle J of each electric lever F is operatively connected with one or more of the locking bars 1 in the locking bed B. As shown in the drawing this connection comprises a driver crank 11 rigidly attached to spindle J, a rod 12 operated by this driver, and a segmental gear 13 operated by rod 12 and meshing with a rack on one of the locking bars 1. 100 105

The lower compartment of each frame section G contains indication lamps L which are used in connection with the electric

levers F. As here shown, each lamp L is supported in a housing 16 which housing is in turn supported by a front plate 15 provided with a transparent cover 14 through 5 which the lamp may be observed. The front plate 15 is secured to the frame G by means of screws, thus allowing the housing 16 to extend into the lower compartment of frame section G.

Extending the length of frame G and fastened in the upper half thereof is a strip 17 of some suitable insulating material such as impregnated wood. Parallel with this strip and fastened thereupon by means of screws 19 are a plurality of spaced bus bars 18 for the electrical control of the associated lamps or other apparatus. The compartment containing these bus bars is covered by a substantially flat sheet of metal 20. The arrangement of the indication light L and the bus bars 18 are clearly indicated in Fig. 3.

When an electric lever F is omitted, as indicated in the right hand section of Fig. 1, the associated lamps L are also omitted and a blank sheet of metal is fastened to frame section G as at 21, Fig. 1, in place of the front plates 15 of the corresponding lamp housing 16.

As stated hereinbefore, the legs D are equally spaced, and each frame G extends from the middle of one leg to the middle of an adjacent leg. It follows that all of the sections of this frame may be identical, and so the frame may be made up of standard units comprising a frame section G and a back plate E of the same length and width. A machine of any required size (number of levers) may, therefore, be constructed by using the suitable number of frame sections G, thus eliminating the necessity for the manufacture of a special section for each

length of machine. Furthermore, when a machine is to be enlarged, that is, when more mechanical levers are to be added, 45 one or more sections are added to the framework C as usual, and it is then necessary to merely add a frame section G and back plate E for each additional unit of the framework C. 50

Although I have herein shown and described only one form of machine embodying my invention, it is understood that various changes and modifications may be made therein, within the scope of the appended 55 claims without departing from the spirit and scope of my invention.

Having thus described my invention, what I claim is:

1. In an interlocking machine having 60 electric levers, a super-structure comprising a horizontal frame open at the front and having a horizontal rib dividing the frame into two horizontal compartments located one directly above the other, bus bars in 65 one said compartment associated with the electrical portions of the machine, cover plates for the other compartment having openings, and indicating lamps supported by said cover plates and located behind 70 said openings.

2. In an interlocking machine having electrical levers, a super-structure comprising a horizontal frame open at the front and having a horizontal rib dividing the frame into two horizontal compartments located one directly above the other, bus bars in 75 one said compartment associated with the electrical portions of the machine, and indicating lamps located in the other compartment and associated with said electric levers. 80

In testimony whereof I affix my signature.
WILLIAM C. McWHIRTER.
